ROYDEN O. COUCH, OF GRANT, FLORIDA

LOW-HEAD ROTARY PUMP

Application filed December 27, 1930. Serial No. 505,051.

The object of this invention is to produce a pump which may be installed in places where water is to be raised only a comparatively small distance, that is, not more than 5 a few feet. The pump is intended to be used particularly in outdoor places where the water is to be raised for drainage or for irrigation purposes.

A further object of the invention is to provide a pump which may be easily and quickly installed in the desired position so that the water may be raised from a stream, canal, tank or other body of water to a slightly higher point in the same or another canal, 15 stream or conduit.

A further object of the invention is to provide a pump so that the intake and discharge portions of both may be submerged, with the result that the actual head required to be overcome by the pump is not increased by 20 any unnecessary lift of the water. This together with very short pump sections allows maximum efficiency to be obtained and a large amount of water can be raised and discharged with a smaller amount of power 25 than has apparently heretofore been possible.

For a detailed description of one form of my invention which I deem is preferable, 30 reference may be had to the following specification and to the accompanying drawings forming a part thereof, in which

Figure 1 is a vertical, sectional view of my improved pump casing and the rotor member thereof being shown in elevation;

Fig. 2 is a vertical, sectional view of the outer casing taken on a radial vertical plane of the device, as shown in Fig. 1 and substantially at the point indicated by the line 2—2, 40 Fig. 4;

Fig. 3 is an elevational view showing the rotor of the pump in elevation and the stationary plates thereof and a portion of the outer casing in section;

Fig. 4 is a horizontal sectional view taken substantially on the line 4—4, Fig. 1; and

Fig. 5 is a vertical elevation of the outer housing or casing as seen from the same position as the sectional view of Fig. 1.

Referring to the drawings, the numeral 1

indicates a substantially cylindrical housing or casing of sheet metal, the lower portion of which is provided with the openings 2 and 2' for the egress of water. The outer casing 1 is also provided just above the outlets 2 and 2' with a partition or diaphragm 3 which prevents the water from entering the upper part of the casing and forms a guide for the outflow of the water.

The amount of flow of the water through the openings 2 and 2' is controlled by slideable gates in the form of rectangular plates 4 and 4'. These are adapted to slide vertically in the grooves or channels 5 and 5'. Each of the plates 4 and 4' is provided near its lower edge with lugs 6, to which are attached suitable connecting rods 7 which carry at their upper ends an eye 8 forming a bearing which receives a pin or bolt 9, so that the rods 7 are pivotally connected with a vertical bar 10 which is also pivoted at 11 to a lever 12 carried by a curved support 13. There are preferably four of these curved supports 13, the lower ends of which are connected with a cylindrical casing 1 and the point at which they unite at the top carries a bearing 14 for the vertical driving shaft 15.

From the above it will be appreciated that when the lever 12 is raised the plate or gate 4 will be raised correspondingly to uncover more or less of the opening tube. This will allow a control of the flow of water from within the casing 1.

As indicated in the drawings, there are preferably four of these gates 4 and 4' located in slightly less than 90° of the circumference of the casing and any one of the gates may be operated independently of the others. The lower part of the external casing is slightly enlarged as indicated at 16 and is also provided with four openings 17 and 17'. These openings are also adapted to be covered by gates similar to those above described and indicated at 18 and 18'. These gates are operated in a similar manner to the upper gates through the connections comprising the rods 19, the bar 20 and the lever 21, which is also connected to the curved support 13. Each of the four lower gates 18 and 18' is similarly operated and covers slightly less than 90°.

of circumference of the lower portion of its casing 16. The bottom of the casing is preferably closed by a curved plate 22 which has a central conical projection 23 and forms a bearing for a stationary hub member 24. Attached to the hub member is a series of radial vanes 25, preferably four in number, the outer ends of which are attached to the tubular curved portion of the conduit 26, the upper margin of which is extended horizontally to provide a partition or diaphragm 27. Thus the vanes 25 are held rigidly in position in the manner indicated in Figs. 1 and 3. The hub 24 carries a cylindrical recess or socket within which is contained a rubber bushing 28 which is lined with a bronze or non-corrodible metal 29 which forms a bearing for the lower end of the drive shaft 15.

On the drive shaft 15 is fixed a hub 30 and said hub 30 carries a series of vanes 31, preferably four in number, which constitute the rotor or propeller member of the pump. The outer ends of these vanes are preferably machined so that they fit accurately but movably within the cylindrical portion of the conduit 26, as indicated in Fig. 4. Above the hub 30 and surrounding the shaft 15 is a second fixed hub 32 which is also provided with a rubber bushing 33 and a metallic bearing or other bushing 34 similar to those in the lower fixed hub 24. Radiating from the hub 33 is a series of inclined guide vanes 35, preferably five in number, which serve to guide the water upward and prevent unnecessary rotation of the water or reverse currents thereof. The outer ends of these guide vanes are also attached to the conduit 26, and thereby hold the hub 32 in fixed position. The upper end of the hub 34 receives the lower end of a tube 36 which surrounds the drive shaft 15 which is preferably provided at the top with a roller or ball-bearing 37 (the details of which are not shown). The drive shaft 15 is also provided with a suitable drive pulley 38 to receive a suitable belt from the power mechanism such as an electric motor or other device. It is obvious, of course, that the armature of an electric motor may be mounted directly on the drive shaft 15 in place of the pulley 38.

From the above description it will be apparent that when the driving pulley 38 is rotated, the shaft 15 and the vanes 31 are also rotated and the movement of the vanes 31 from right to left in Fig. 1 or in a clockwise direction in Fig. 4 will cause the water to be drawn through the openings 17 and 17' through the conduit 26 and from there discharged above the diaphragm 27 so that the water will be caused to flow outward through the openings 2 and 2', depending on which ones are open or closed.

As indicated in Fig. 4 the concrete piers or walls 40, 41, 42 and 43 may constitute dividing walls at the crossing point of two canals,

one canal being located between the walls 40 and 41, and 42 and 43, the other canal being located between the walls 40 and 42, and 41 and 43. In this case when the lower gates 4 are opened, the upper gates 18 closed, the lower gates 4' closed and the upper gates 18' opened, the water will flow from the portions of the canal A—B into the lateral canals C—D. Obviously this flow of water may be reversed or water may be distributed in any other desired way by the corresponding manipulation of the various gates. It will be appreciated that the water may be similarly raised from one passage to another passage or from the lower portion of one canal to a higher portion of the same canal extending in the same direction as the first, in which case, of course, only diametrically opposite gates are necessary. It is also obvious that water may be taken in at all points through the lower part of the casing and distributed through as many points as may be required from the upper part of the casing by applying the necessary number of gates corresponding to the number of outlet passages or channels of flow.

It is preferable that the lower portion of the casing containing the gates 18 and 18' be entirely submerged in the intake water as indicated in Fig. 1 and the upper portion of the casing may be entirely or only partly submerged in the body of water forming the discharge channel or channels. From the above arrangement it will also be apparent that much advantage is obtained in the shape and arrangement of the fixed and rotary vanes of the pump since the edges of the rotary vanes move in close proximity to the edges of the fixed vanes, thereby permitting the plates to be easily cleared of grass, weeds, moss and small trash which would otherwise tend to clog the rotor or vanes of the pump. Thus the rotor plates are automatically cleaned as they pass the edges of the stationary plates on each side thereof. This fact is of great value where the pump is used as a drainage pump, where the water being drained may carry a greater or less quantity of débris in the form of grass, leaves, weeds, moss, etc.

Having thus described this form of my invention, I do not wish to be understood as being limited to the details of form and arrangement of the parts set forth, for various changes may be made by those skilled in the art without departing from the spirit and scope of my invention.

What I claim is new and desire to protect by Letters Patent is:—

1. In an hydraulic turbine pump having a draft and discharge conduit in which is a turbine rotor, the improvement which comprises, providing an external vertical housing having a transverse diaphragm the opening in which communicates with said con-

duit, the walls of said housing having guides extended above said diaphragm and having a plurality of angularly disposed inlet and outlet openings above and below said diaphragm, and independently movable gates for each of said openings in said housing and slideable in said guides which form supports therefor, whereby the points at which the water enters and leaves said housing 10 may be determined.

2. In an hydraulic turbine pump having a continuous draft and discharge conduit in which is a turbine rotor, the improvement which comprises, providing an external columnar housing having a transverse diaphragm substantially intermediate the ends thereof, the opening in which communicates with the walls of said conduit, said housing having a plurality of angularly disposed inlet and discharge openings below and above said diaphragm and independently and vertically adjustable gates slideable on said housing and adapted to form closures for each of said inlet and discharge openings respectively.

3. In an hydraulic turbine pump having a draft and discharge conduit in which is a turbine rotor, the improvement which comprises, providing an external substantially cylindrical housing having a plurality of angularly disposed openings in each of the vertical walls thereof above and below said conduit which is centrally located in said housing, a transverse annular diaphragm intermediate said openings and forming an horizontal extension of the upper end of said conduit intermediate the ends of said housing, vertically and independently movable gates adapted to form adjustable closures 40 for each of said openings respectively to control the direction of the inward and outward flow of water therethrough, and means at the top of said housing connected respectively and independently with said gates for adjustment thereof in vertical directions.

4. In an hydraulic turbine pump having a draft and discharge conduit enclosing a turbine rotor member, the improvement which comprises, an external housing enclosing 50 said conduit, a diaphragm across the intermediate portion of the interior of said external housing and having a central opening therein, said conduit communicating with said opening, fixed guide vanes in said conduit above and below said rotor and in close proximity thereto, said external housing having a plurality of angularly related orifices therein below and above said diaphragm for the intake and outflow of water, and vertically adjustable gates adapted to cover more or less of each of said orifices to control the points of the inward and outward flow of water therethrough.

Signed this 23rd day of December, 1930.

65 ROYDEN O. COUCH,
